UNITED STATES PATENT OFFICE.

D'ARCY PORTER, OF CLEVELAND, OHIO, ASSIGNOR TO THE WHITE SEWING MACHINE COMPANY, OF SAME PLACE.

SEWING-MACHINE TABLE.

SPECIFICATION forming part of Letters Patent No. 323,529, dated August 4, 1885.

Application filed January 26, 1885. (No model.)

To all whom it may concern:

Be it known that I, D'ARCY PORTER, of Cleveland, in the county of Cuyahoga and State of Ohio, have invented certain new and useful

- 5 Improvements in Sewing-Machine Tables; and I do hereby declare the following to be a full, clear, and exact description of the invention, such as will enable others skilled in the art to which it pertains to make and use the same.
- 10 My invention relates to sewing-machine tables; and it consists in an improved metal frame-work composed of cast-metal plates for supporting the drawers and bolts or rods for securing the plates together, the whole suspended from the under side of the table.

15 In the drawings, Figure 1 is a detached perspective view of my invention, arranged for the accommodation of two drawers, with one drawer in place. Fig. 2 is a view in vertical cross-section of the same, with two drawers in place. Fig. 3 is a detached view of the metal tubing by which the bolts are covered. Fig. 4 is a detached view of one of the bolts or rods by means of which the parts are held 25 together. Fig. 5 is a perspective view of a sewing-machine table with a nest of three drawers suspended from it by my improved mechanism. Fig. 6 is a detached view of the upper side of one of the cast-metal plates.

30 In the drawings, A represents the drawers of a sewing-machine table that are suspended from the under side of the table; A', the sides of the drawers, and A' the bottom of the same.

35 B represents one of my improved cast-metal plates, that is intended to support the drawer. This plate is provided upon its upper side with a guide-flange, B', in the form of a parallelogram, upon which the drawers slide and 40 which prevent the lateral displacement of the drawers, as the sides A' of the drawers are so constructed as to extend below the bottom A' and bear against the guide-flange B', as shown in Fig. 2 of the drawings. The cast-metal

45 plate B is also provided with holes B', for the passage of the bolts or rods C, and also with the elongated opening or slot B', for the passage of a lock-bolt. The locks may be attached

to alternate drawers, and the bolt passing through the opening B' may lock the drawer 50 above as well as the drawer to which it is secured; or each drawer may be supplied with a lock.

C C C C are bolts or rods for securing the lower plates, B B, to the top plate, E. These 55 rods may be made in the form of a bolt and provided with a head at one end and a thread and nut at the other, as shown in the drawings, Figs. 2 and 4, or in the form of a rivet.

D D are tubular rods cut the proper length 60 to separate the cast-metal plates B and E the proper distance to admit the drawers A. The rod or bolt C passes through these tubular rods D, as shown in Fig. 2. The upper end of the tubular rod D bears against the lower 65 side of the upper plate, while the lower end rests upon the upper side of the lower plate, thereby preventing these plates from being drawn together by the bolt or rod C closer than the length of the tube D. 70

The upper plate, E, is provided with screw-holes E', by means of which it is secured to the under side of a sewing-machine table by ordinary wood-screws.

The plates B and E and tubular rods D may 75 be nickel plated, or the plates B and E may be japanned and ornamented, and the tubular rods plated, thereby making the device highly ornamental.

In the drawings I have shown my device as 80 constructed for two or three drawers. It is equally adapted for any number of drawers by adding the necessary number of plates B and lengthening the rods C.

Having described my invention, what I claim 85 is—

1. The combination, with a sewing-machine table, of a drawer-support consisting of metal plates connected together by means of bolts and secured to the under side of the table, 90 substantially as and for the purposes shown and described.

2. In a sewing-machine table, a drawer-support suspended from the under side of the table, consisting of the metal plates B, provided with a guide-flange, B', said plates con- 95

nected together and supported by bolts, substantially as shown and described.

3. In a sewing-machine table, a drawer-support suspended from the under side of the table, and consisting of metal plates connected together by bolts, and the tubular rods D, surrounding the bolts and separating the plates, substantially as shown and described.

In testimony whereof I sign this specification, in the presence of two witnesses, this 17th day of January, 1885.

D'ARCY PORTER.
